UNITED STATES PATENT OFFICE.

HORACE T. THOMAS, OF LANSING, MICHIGAN, ASSIGNOR TO REO CAR CO.,
OF LANSING, MICHIGAN, A CORPORATION OF MICHIGAN.

COOLER.

No. 851,844.

Specification of Letters Patent.

Patented April 30, 1907.

Application filed December 21, 1905. Serial No. 292,710.

To all whom it may concern:

Be it known that I, HORACE T. THOMAS, a citizen of the United States of America, residing at Lansing, in the county of Ingham and State of Michigan, have invented certain new and useful improvements in Coolers, of which the following is a specification, reference being had therein to the accompanying drawings.

10 This invention relates to coolers designed for cooling liquid by circulating it through tubes exposed to the air; and the particular object I have in view is to produce a cooler of the sectional type which is cheap to manufacture, efficient, frost proof, and otherwise well adapted for use on automobiles and the like.

20 My invention has particular reference to a novel form of expandible tubes, to the novel manner of constructing the cooler in sections and units, and to the means of increasing the cooling surface of the tubes, all as more fully hereinafter described and shown in the accompanying drawings and more specifically set forth in the claims.

25 In the drawings Figure 1 is an elevation of my improved cooler with the middle portions of the tubes broken out to present it in a smaller compass; Fig. 2 is in part an end elevation, being the end shown at the right in Fig. 1, and in part (comprising four tiers of headers) a vertical section through the same in a plane parallel to that of the elevation; Fig. 3 is a top plan of Fig. 1, the middle portion of the tubes being broken out; Fig. 4 is a detached elevation of one of the headers; Fig. 5 is a cross section on line $x-x$ Fig. 4; Fig. 6 is a detached elevation of one of the radiating fins, and Fig. 7 is a cross section of Fig. 6 on line $y-y$.

30 In the drawings A A' represent the tubes composing the cooler and B B' B² the heads connecting the tubes into a circulating system, the former being preferably of drawn brass and flattened and the latter being of cast brass. The tubes A A' are flattened their whole length except at the ends, which are expanded to a circular cross section and constitute tubular nipples a by means of 35 which the tubes are connected to the headers. The headers B, shown in detail in Figs. 4 and 5, are of tubular shape and have closed rounded ends terminating in flattened and apertured ears b .

On one side in the plane of the ears the 55 header is provided with a plurality of flanged side openings c adapted to receive the nipples a of the tubes, and in the middle at right angles to said plane the header is formed with an apertured boss d for connecting it 60 with another header, as will be more fully described hereinafter.

The headers B' are exactly like the headers B except that they have apertured bosses d on both the upper and lower side for connecting with the headers above and below. The headers B², which are the first and the last of the series, are similar to the headers B except that they are preferably a little larger and cast with inlet and outlet arms $e f$ respectively for connection with the inlet and outlet pipes of the cooler; and on account of these arms the tubes A' are a little shorter than the tubes A. The header B² at the bottom is provided in addition with a drain- 75 age cock g .

35 The cooler is built up in horizontal tiers or sections each comprising two headers with the tubes uniting them together, the drawings showing four tubes for each section, the 80 tubes being so connected with the headers that their flattened sides are in the horizontal plane. The cooler is built up of these sections which are connected in the following manner: Beginning on top at the right, the 85 uppermost header B' which has the inlet is connected with the header next below and the last one at the bottom, which has the outlet, is connected to the one next above it. At the left all the headers are connected together in groups of four. The connections being thus arranged, it will be seen that 90 the heated medium, after entering the top header B² at the right has its circulation split up into eight tubes leading from the 95 two connected top headers to the two corresponding headers on the left, thence the circulation takes its course in the opposite direction through the eight tubes comprising the two tiers next below and so on back and forth as indicated by the arrows, finally 100 passing out through the outlet from the bottom header at the right. The circulation is thus taking place from the top downward back and forth through two sections 105 at a time which split it up into eight tubes, the two sections together thus forming a unit of circulation.

I preferably provide the tubes with radiating fins C which are made of metal sheets punched out with openings h corresponding to the shape and position of the tubes in each section so that each fin extends across all the tubes of one section. The fins may be provided with corrugations i and the openings h are formed with standing flanges h' around them to form an extended metallic contact with the tubes. It will be obvious that these fins have to be strung upon the tubes before the ends of the latter are expanded into the round shape.

The cooler is formed into a rigid structure by means of tie rods D which pass through the apertured ears b of the headers and the different groups of headers are spaced apart by means of spacing thimbles E upon the tie rods, the whole being clamped together by means of suitable nuts and washers upon the ends of the tie rods. These tie rods also form convenient means for securing the cooler in position by engaging with suitable supports G and stays H.

The tubes having the rounded ends are readily secured to the headers by means of soldering or brazing and the connections between the headers are made tight by means of short thimbles inserted into the apertures of the connecting bosses and by placing washers of soft copper or like material between the joints and clamping them fast between the headers by means of the tie rods.

It will be seen that my cooler is built up of a vertical series of horizontal tiers or sections each composed of a plurality of flattened tubes and two headers connecting the opposite ends of the tubes in parallel; further, the sections are connected in pairs by means of connections between the heads of adjacent sections and each pair of sections thus united form together a unit, which units are connected in series by means of connections between adjacent headers of the units; and the capacity of the cooler may thus be readily varied by varying the number of units to suit the requirements.

My construction is particularly designed and adapted for use on automobiles; it is not liable to leakage either from expansion or contraction of the parts or from jolting; it is very compact, offers great facility for supporting and connecting it in position and by reason of its having expandible tubes; it is practically frost proof and forms a cooler of great surface compared with its liquid capacity.

Having thus fully described my invention, what I claim is:—

1. A sectional cooler composed of a vertical series of horizontally arranged sections each consisting of a plurality of tubes and two tubular headers transversely uniting them at their opposite ends, the tubes being

flattened between their ends in the horizontal plane of the section and the ends thereof being expanded and forming nipples of circular cross section and the headers being formed with corresponding lateral openings adapted to receive said nipples and form therewith the connection with the tubes, the sections being connected into a circulatory system by means of vertical connections between the headers. 75

2. A sectional cooler composed of a vertical series of horizontally arranged sections, each consisting of a plurality of tubes and two tubular headers transversely connecting the tubes at their opposite ends, said headers provided midway their length with apertured bosses adapted to connect the header in vertical alinement with the headers of adjacent sections, the header at one end provided with two such bosses on opposite sides adapting the sections to be united in pairs forming units. 80

3. A cooler composed of a vertical series of horizontally arranged sections each consisting of a plurality of tubes and cast tubular headers transversely connecting the tubes together at their opposite ends, said headers formed with closed ends provided with flattened ears for the reception of tie rods and with apertured bosses midway of their length 95 adapted to connect the header with the header of an adjacent section or sections in vertical alinement therewith.

4. A cooler composed of a vertical series of units, each composed of a plurality of like superposed sections, each section consisting of a plurality of tubes and two headers transversely uniting the opposite ends of said tubes upon a horizontal plane, the headers of the sections being provided upon their adjacent faces midway of their length with apertured bosses adapted to connect and support the headers in vertical alinement with each other. 100

5. A cooler composed of a vertical series of units each composed of a plurality of superposed sections each section composed of a plurality of tubes extending in a horizontal plane and two cast headers transversely uniting the same and formed with apertured ears 115 at their opposite ends and with connecting bosses midway of their length whereby the units are alternately united together at opposite ends in series with each other and the tubes of each unit are united together in parallel with each other, tie rods passing through the ears of the headers and spacing thimbles interposed upon the tie rods in the open spaces between the units. 120

6. A cooler composed of a vertical series of units each composed of a plurality of superposed sections, each section composed of a plurality of flattened tubes extending in a horizontal plane and two tubular headers transversely uniting the same at opposite 125 130

ends, said headers provided with closed ends terminating in flattened ears and with connecting bosses midway of their length whereby the units are connected in vertical series 5 with each other and with the tubes of each unit in parallel, vertical tie rods passing through the ears of the headers and adapted to clamp the sections together, spacing thimbles upon the tie rods in the open spaces between the units, and fins extending across the tubes of each section and common to all the tubes thereof.

7. A cooler composed of a vertical series of units each composed of two superposed sections each consisting of a series of flattened tubes formed with ends of circular cross-section and two cast headers transversely connecting the opposite ends of the tubes upon a horizontal plane, the headers being formed 15 with ears at the ends and with connecting bosses, the unit being formed by the headers

at each end being connected together midway of their length by means of connecting bosses formed upon their adjacent faces and the units being connected together in series 25 with each other by means of like connecting bosses formed on adjacent headers of the units, tie rods passing through the ears of the headers, spacing thimbles upon the tie rods in the open spaces between the units, fins extending in one piece across the tubes of each section and provided with flanged openings for the passage of the tubes therethrough and inlet and outlet arms integrally formed with the terminal headers and extending in horizontal planes. 30

In testimony whereof I affix my signature in presence of two witnesses.
